COMBINATION PADLOCK

Antonio Diaz, Habana, Cuba

Application February 29, 1932. Serial No. 595,916

2 Claims. (Cl. 70—113.)

This invention relates to combination padlocks and has for the primary object, the provision of a device of the above stated character which will be burglar-proof, easy to lock and unlock when having knowledge of the proper combination, and is so constructed that the combination may be easily and quickly changed without substitution of new parts and also permits a large number of different combinations to be had.

10 With this and other objects in view, this invention consists in certain novel features of construction, combination and arrangement of parts to be hereinafter more fully described and claimed.

15 For a complete understanding of my invention, reference is to be had to the following description and accompanying drawings, in which

Figure 1 is a side elevation illustrating a combination padlock constructed in accordance with 20 my invention.

Figure 2 is a sectional view taken on the line 2—2 of Figure 1.

25 Figure 3 is a perspective view illustrating a connecting element between the end members of the body and carrying a locking element or key and a series of key retaining elements.

Figure 4 is a vertical sectional view illustrating the lock.

30 Figure 5 is a detail sectional view taken on the line 5—5 of Figure 4.

Figure 6 is an end view illustrating one of the permutation elements.

Figure 7 is a sectional view taken on the line 7—7 of Figure 6.

35 Figure 8 is a plan view illustrating a locking ring.

Figure 9 is a similar view illustrating one of the spacing elements.

40 Figure 10 is a plan view illustrating the locking element or key.

Figure 11 is a detail view illustrating one end of the shackle.

Figure 12 is a side elevation illustrating the application of an element to the lock for permitting the combination to be easily actuated when the figures or characters cannot be easily read.

Figure 13 is a perspective view illustrating the element.

45 Referring in detail to the drawings, the numeral 1 indicates a body of cylindrical shape having adjacent each end a shackle socket 2 to receive the ends of a substantially U-shaped shackle 3. Portions of the legs of the shackle are reduced as shown in Figure 4 to enter the sockets 2 and providing annular shoulders 4 on the shackle to abut the outer wall of the body to limit the inward movement of the reduced portion of the legs into the sockets 2. One of the leg portions is shorter than the other leg portion and adjacent its free end is provided with

a notch 5 having a bevelled wall and an abrupt or rightangle wall relative thereto so that when the locking key or element 6 is arranged within the notch 5 the outward movement of the shackle is prevented. The other leg of the shackle is provided with a notch 7 corresponding in shape to the notch 5 and also adapted to receive the key or locking element 6, thus it will be seen that both ends of the shackle may be locked within the body. The last named leg portion of the shackle is provided with a reduced portion 8 having a bevelled wall 9 at one end and an abrupt or rightangle wall 10 at the opposite end. A spring pressed pin 11 is carried by the body 1 and fits within the recess 8 and is adapted to allow the inward movement of the shackle relative to the body but which will limit the outward movement of the shackle when engaged with the shoulder 10 to prevent complete separation of the shackle from the body. The right angle or abrupt shoulder 10 is located adjacent the end of the respective leg portion of the shackle and has a slot 12 extending therethrough for the purpose of receiving the spring pressed pin 11, and thereby allowing the passage of the said end of the shackle by the plunger 11 when desiring to disconnect the shackle entirely from the body 1. It is to be understood that the shackle must be turned into a proper position to bring the slot 12 in alignment with the spring pressed key either when connecting or disconnecting the shackle entirely from the body 1.

50 The body 1 consists of end members 13 having sockets 14 formed in their opposing faces to receive a connecting element 15 and the latter is retained within said sockets by set bolts 16 carried by the end members. The end members have formed therein the shackle receiving sockets 2 and the connecting element 15 is provided with shackle openings or passages 17 aligning with the shackle sockets 2. The connecting element is of cylindrical shape and is provided with oppositely arranged grooves 18 and also a key groove 19. The grooves 18 and 19 open outwardly through the ends of the connecting element 15 and the key groove 19 slidably receives the key or locking element 6 which is provided on one edge with relatively spaced teeth 20 that project outwardly of the key groove 19. The opposite edge of the key 6 from the teeth 20 and adjacent one end is provided with a notch 21 and arranged opposite to the notch 21 and upon the same edge of the key 6 as the teeth 20 is a projection 22 adapted to slide within a chamber 23 formed in one of the end members 13 of the body 1 and is in communication with the recess of the respective end member. A plunger 24 is slideable in a chamber 23 and through an opening in the end of the respective end member for the purpose of permitting a person to manually slide

the plunger in one direction and to position the key or locking element 6 within the notches 5 and 7 of the shackle for the purpose of locking the shackle against relative movement to the body. Figure 2 shows the key or locking element positioned to secure the shackle to the body against relative movement thereto.

Bearing portions 25 are formed on the opposing faces of the end members 13 of the body and engage the connecting element 15 as shown in Figure 2. Annular spacing elements 26 are mounted on the connecting element 15 and which are provided with oppositely disposed lugs 27 fitting within the grooves 18 of the connecting element to prevent said spacing elements from having rotation relative to the connecting element. The spacing elements 26 are provided with notches 28 aligning with the key groove 19 for the purpose of permitting the key to have sliding movement endwise relative to the connecting element. Annular locking elements 29 are mounted on the connecting element 15 between the spacing elements 26 and are cut or severed to form relatively spaced ends 30. The ends 30 being relatively spaced provide passages which when aligned with the key groove 19 permit the key to have endwise movement relative to the connecting element 15.

A series of annular operating elements 31 are rotatably mounted on the spacing elements 26 between the end members 13 of the body with the locking elements 29 confined therein and having frictional contact therewith. The frictional contact of the locking elements 29 with the operating elements 31 is sufficient to cause the locking elements to rotate on the connecting element 15 by the rotation of the operating elements and the latter are provided with a series of characters as shown in Figure 1 adapted to cooperate with a series of characters on the end members 13. The operating elements 31 are provided with finger pieces 32 whereby a person can conveniently rotate the various operating elements relative to each other for aligning certain characters of a combination and with the characters on the end members of the body.

A person familiar with the proper combination of the lock rotates the various operating elements 31 until the characters of the combination align which positions the passages of the locking elements in alignment with the key groove 19 of the connecting element 15 and on tilting the locking endwise, the key gravitates into a position to become disengaged from the notches 5 and 7 of the shackle, thus allowing the shackle to be moved outwardly relative to the body and freeing one end of the shackle that the same may be removed and replaced in a keeper. To lock the device, the plunger 24 is moved inwardly positioning the key as shown in Figure 2 and by turning several of the operating elements 31, the passages of the locking elements 29 will be moved out of registration with the groove 19 and will lie between the teeth 20 of the key preventing endwise movement of the key.

Should the key fail to slide by gravitation when the lock is tilted upon one end due to some foreign matter, one of the end members is provided with a passage 34 and the operating elements 31 each provided with a series of passages 35 and when the combination has been properly operated, a

straight passage is established to the chamber 23 from the passage 34 whereby a small instrument or wire may be inserted for the purpose of imparting endwise movement to the key.

When it is desired to change the combination, it is only necessary to move the operating elements 31 relative to the operating elements 29 and this can be easily accomplished when the locking elements 29 are so positioned that their ends 30 abut the teeth 20 on the locking element or key 6.

An element 36 is provided for aiding a person in operating the combination of the lock at night time or when the characters on the lock cannot be easily read and is adapted to be positioned against the body of the lock with one edge in engagement with the shackle 3 while the opposite edge is shaped to cause the combination of the lock to be actuated properly when the finger pieces or pins 32 are brought into engagement therewith as shown in Figure 12.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A combination padlock comprising a body having sockets, a shackle of substantially U-shape receivable in said sockets with one leg of a greater length than the other leg and provided with a cut-out portion forming a bevelled face and an annular shoulder having a slot therein, a spring pressed plunger carried by the body and fitting in the cut-out portion to limit the outward movement of the shackle relative to the body and to permit the shackle to be disconnected from the body when the slot is aligned with the plunger, slideable means on the body to engage and disengage with the shackle, and combination means for securing the slideable means in engagement with the shackle.

2. A combination padlock comprising end members having sockets in opposing faces thereof, a connecting element received in the sockets and secured to the end members and having oppositely disposed lug grooves and a single key groove, said end members and element having alining sockets, a shackle received by the last-named sockets and having notches, a toothed key slideable in the key groove to be engaged and disengaged with the notches, spacing elements on said connecting element and having offsets fitting in the lug grooves and each provided with a notch to receive the key, operating members mounted on the spacing elements for rotation relative thereto, locking elements having spaced ends to receive the key and journaled on the connecting element and frictionally engaging the operating members to be rotated thereby, one of the end members having a chamber to receive one end of the key, a lug on said end of the key and located in the chamber, a plunger slideable in the chamber to engage the lug and extending exteriorly of the respective end member to be manually slid for positioning the key in engagement with the notches of the shackle.
